UNITED STATES PATENT OFFICE.

JOHN M. OAKLEY, OF BROOKLYN, ASSIGNOR OF ONE-HALF TO JOHN KEATING, OF NEW YORK, N. Y.

REVERSING-GEARING FOR WASHING-MACHINES.

SPECIFICATION forming part of Letters Patent No. 326,672, dated September 22, 1885.

Application filed July 28, 1885. (No model.)

To all whom it may concern:

Be it known that I, JOHN M. OAKLEY, a citizen of the United States, residing at Brooklyn, in the county of Kings and State of New York, have invented a new and useful Improvement in Reversing-Gearing for Washing-Machines and for other Purposes, of which the following is a full, clear, and exact description, reference being had to the accompanying drawings, forming a part of this specification.

My invention relates to improvements in that class of gearing to be applied to washing-machines in which a stationary shell and an inner revolving cylinder are used, whereby the inside cylinder is made to revolve in opposite directions automatically and alternately, as will be more fully hereinafter described.

The object of my invention is to produce a cheap, simple, and durable device whereby the inside cylinder of a washing-machine or an agitating-machine is made to revolve in opposite directions automatically and alternately or continuously, and with suitable gears and cam-wheel, starting, stopping, and locking devices, and one that can be operated by unskilled labor.

Figure 1 is a perspective view of a cylinder washing-machine with my invention attached. Fig. 2 is a side view or elevation of the reversing mechanism. Fig. 3 is a view of the cam-wheel. Fig. 4 is a view of the starting, stopping, and locking device.

A, Fig. 1, represents the outer casing or tank, in which is contained the revolving or inside cylinder, B, both being constructed of wood or other suitable material. The inside cylinder is journaled at both ends of the casing A, and at one end the journal-shaft extends out through the end of the outer casing far enough to receive the gear-wheel C. This gear-wheel is firmly keyed to the journal-shaft, as shown at C', Fig. 1, and meshes with a pinion, D, keyed to the pulley-shaft, by which means the cylinder B will be caused to revolve, as more fully described hereinafter.

E is an iron frame, made of one or more pieces of metal with journal and bolt holes through it, and with means to attach it firmly to the end of the casing A, and of sufficient

strength to support the pulley-shaft and other gearing, as shown in Figs. 1 and 2.

F is the pulley-shaft, which is journaled into and revolves in the frame E. At or near one end of this shaft and within the frame is the pinion D, firmly keyed to it. At the opposite end is a worm or screw, D'. This worm is made upon the hub of the pulley-wheel G², the object of which is described hereinafter. Near the center of the shaft F are the pulley or band wheels G, G', and G². The pulley-wheel G has less face-surface than the pulley-wheels G' and G², and it is firmly keyed to the shaft F. On either side of the pulley G are the two idlers or loose pulleys G' and G², which turn freely on the shaft.

H is a wheel meshing into and operated by the screw or worm D' on the shaft F. This wheel is keyed to a short shaft running at right angles to the shaft F, and supported in the frame E back of the wheel H, and keyed to the same shaft is a bevel or miter wheel, I. This wheel passes partly through the frame E, as shown in Figs. 1 and 2, the frame being cast partly open for the purpose.

J is a cam-wheel having a bevel or miter wheel, I', attached to one side of it, as shown, and revolves on a stud or short shaft screwed into the frame E, the bevel or miter wheel meshing into the corresponding bevel or miter wheel I.

The cam-wheel J is constructed internally similar to a belt-wheel, except the supporting arms being placed near one edge to form or cast on or support a bevel or miter wheel. On the outer surface or face of the cam-wheel, at one edge, a bead is formed, rising up one-half an inch (more or less) and passing around one-third of the circumference, (more or less,) then passing down diagonally across the face of the wheel to the opposite edge, thence around one-third of the circumference, (more or less,) thence at an angle across the face of the cam-wheel to the beginning of the bead, as shown at K, Figs. 1 and 2, thus forming a raised cam-wheel. The same result may be obtained by making a wider-surfaced wheel with a groove cut in it to correspond to the raised bead, but at much greater expense. The top of the frame E is made flat, and it has

two guides or loops above the top, one having a hole through it, as shown at M, Fig. 2. On the top of the flat part of the frame is a moving bar, N, held in place by the guides or loops M, under which it moves when connected to the cam-wheel, as hereinafter described. On the top of this moving bar are two eye-pieces bolted to it at suitable distances apart. Through these eye-pieces is passed a bar or rod having on one end a flattened oval or U-shaped ring, N' and N'', through which the belts are passed. These bars or rods are adjusted by a set-screw in the top of the eye. Near the outer end of the moving bar N is a double eye-piece, O, open through the center. Back of the double eye-piece is a hole through the moving bar corresponding with the hole in the top guide or loop. The outer end of the moving bar is turned up, and a groove or channel is made through the center of the turned-up portion. The object of this groove or channel through the turned-up portion of the moving bar is to allow the outer arm of the weighted lever P to rest in it, thus controlling and preventing a lateral motion, as shown at O', Fig. 2.

P is a weighted lever, having a hole near the bottom and ball or weight on the top, and with two arms rising upward and outward. The outer end of one arm is turned down with a pin at the end. The object and use of the pin are to lock the moving bar N by pressing the pin down through the hole in the guide or loop and into the corresponding hole in the bar. At the outer end of the other arm, and at one side, is a flat piece of metal having a hole and bolt through it. On the top of the bolt, above the side piece, is a thumb-screw, P'. On the bottom of the bolt is a short bar having two frictionless pins, P'', extending a short distance below the bar, as shown. These frictionless pins are made of steel, with a revolving covering or shield around them, and can be turned into the required position by means of the thumb-screw P'. The object and use of the pins are described hereinafter. The weighted lever P having been placed between the double eye-piece near the outer end of the moving bar N and secured by a bolt, the machine is then ready for operation. A double moving bar may be used on the top of the frame, having guide-holes through which the frictionless pins may drop into position, the pins being placed in the arm of the lever, thus dispensing with the short bar and thumb-screw for adjusting the position of the frictionless pins.

All the various parts herein described are made of iron or steel or other suitable material.

To operate my invention, I employ two belts, R and R', as shown by dotted lines in Fig. 2, which belts are driven by appropriate shafting and pulleys in such a manner that the belt R travels in the direction indicated by the arrow on its surface, and the belt R' travels in an opposite direction, as indicated

by its arrow. Should both of these belts be driven by the same shaft, one of them must be crossed in order to obtain this opposite motion. The belts are caused to remain on the idlers or loose pulleys G' and G'' by being passed through the oval or U-shaped rings N' and N'', connected to the moving bar N, said bar being held in position by the guides or loops M on the top of the frame E, through which it moves.

To start the machine, the belts having been properly adjusted, the weighted lever P is thrown forward, carrying the arm near the top of the cam-wheel, the frictionless pins being carried with it. They are adjusted by the thumb-screw, one to each side of the raised bead or cam on the cam-wheel in the act of throwing over the lever P. The bar N is moved back, carrying one belt on the idler G', and the other belt on the driving-pulley G and partly on the idler G'', keeping both in motion. By the movement given through the cam-wheel to the moving bar N the position of the belts is reversed, thus giving two reversed motions to the cylinder B on every revolution of the cam-wheel. The size of the intermediate gearing will regulate the number of revolutions.

To stop the machine, throw the weighted lever P back toward the cylinder. The pin in the end of the lever-arm will enter the hole in the guide or loop M and pass through and into a corresponding hole in the moving bar N, thus locking the movement and leaving the belts on the idlers G' and G''. The advantages of my invention are its simplicity, strength, and cheapness, every movement being positive, and not liable to get out of order, and it can be operated by inexperienced hands.

Having fully described my invention, what I desire to claim and secure by Letters Patent is—

1. In a gearing adapted for reversing the motion of the cylinder in a washing-machine or agitator, the cam-wheel J, having a raised cam or bead, K, upon the periphery and bevel-wheel on one side, and running upon a stud or pin in the frame E, and receiving its motive power through an intermediate bevel-wheel and a worm-wheel running at right angles, and a worm on the pulley-shaft F and operated by the pulley G, substantially as shown and described.

2. In a reversing-gearing for washing-machines, the weighted lever P, having a hole near the bottom and a ball or weight on the top, and having two arms rising upward and outward, the said arms provided with a pin at the end of one arm and one or more frictionless pins at the end of the other arm, in combination with the moving bar N, provided with belt-shifters N' and N'', substantially as described.

3. In reversing mechanism for washing-machines and for other purposes, the cam-wheel J, having bevel or miter wheel I', in

combination with the weighted lever P, having two arms with pins at the ends, and the moving bar N, provided with eyes to receive the belt-shifters and weighted lever, and with a 5 groove or channel at the end of the moving bar, constructed and arranged substantially as shown and described.

4. In reversing mechanism for washing-machines, the combination of the following 10 parts, viz: the cam-wheel J, with bevel-wheel I', the weighted lever P, with its starting and

locking devices, the moving bar N, with its belt-shifters, the bevel-wheel I and worm-wheel H on right-angle shaft, the worm D', pulley-wheels G, G', and G², shaft F, with pinion D and frame E, gear-wheel C, and cylinders B and A, all constructed and arranged substantially as shown and described. 15
